Primary Examiner — Elizabeth A. Albert(74) *Attorney, Agent, or Firm* — Paul R. Martin(57) **CLAIM**

The ornamental design for a page retainer clip, as shown and described.

DESCRIPTION

FIG. 1 is a perspective view of the page retainer clip showing my new design.

FIG. 2 is another perspective view thereof.

FIG. 3 is a top plan view thereof.

FIG. 4 is a bottom plan view thereof.

FIG. 5 is a front elevational view thereof.

FIG. 6 is a back elevational view thereof.

FIG. 7 is a right side elevational view thereof; and,

FIG. 8 is a left side elevational view thereof.

The broken lines in the drawings show an environmental feature that forms no part of the claimed design.

1 Claim, 8 Drawing Sheets(56)
